UNITED STATES PATENT OFFICE

ISIDORE FRIED, OF NEW YORK, N. Y.

LATCHING MEANS FOR DUMB-WAITER DOORS

Application filed June 20, 1929. Serial No. 372,481.

This invention relates to a dumb-waiter door latching means.

The principal object of the invention is the provision of means of the indicated character, which is designed and adapted to normally retain all of the doors of a dumb waiter shaft closed against being opened by the tenants of the apartments of an apartment house or dwelling, but which doors may be selectively unlatched by the janitor or superintendent at his station in the basement, to bring about the proper use of the dumb-waiter for any of its numerous purposes.

Some of the other objects of the invention are the provision of means of the indicated character which will be easy to install, which will be reliable in operation, and which may be readily repaired whenever the occasion arises.

With the foregoing and other objects in view, the invention resides in the particular provision, relative disposition and operation of the parts hereinafter fully described and illustrated in the accompanying drawings, in which

Figure 1 is a vertical section of a dumb-waiter shaft equipped with the latching means of the present invention, portions of the shaft and said means being broken away.

Fig. 2 is an enlarged horizontal sectional view taken on the line 2—2 of Fig. 1.

Fig. 3 is an enlarged horizontal sectional view taken on the line 3—3 of Fig. 1.

Fig. 4 shows the double latch which controls two doors.

Fig. 5 is an enlarged vertical section through the lower part of the casing of the latch means, and including the latch for the door of the first floor apartment.

Fig. 6 is an enlarged horizontal section taken on the line 6—6 of Fig. 5.

Fig. 7 is a vertical section, the section being indicated by the line 7—7 of Fig. 6.

Fig. 8 is an enlarged horizontal section taken on the line 8—8 of Fig. 5.

Fig. 9 is a vertical section, the section being indicated by the line 9—9 of Fig. 8.

Fig. 10 is a detail section taken on the line 10—10 of Fig. 9.

Fig. 11 is a perspective view of one of the single latch elements.

Figs. 12 and 13 are plan views of the latch elements of the double latch.

It is to be understood that the invention will be designed and adapted for latching and unlatching any number of doors of a dumb-waiter shaft, the number of doors depending upon the number of apartments which communicate with the interior of the dumb-waiter shaft, whether there be one or two apartments at each floor which communicates with the dumb-waiter shaft.

The illustrated embodiment of the invention is by way of example only. It will be apparent that there is shown a dumb-waiter shaft 10 which extends from the basement to the uppermost apartment. In the present instance there are two doors 11 affording access to the interior of the shaft 10 by two tenants of the top floor, whereas there is one door 11 affording access to the interior of the shaft 10 by the tenants of the remaining lower floors. Each of the doors 11 has a keeper 12 secured to the inside thereof. The latch means which cooperates with the keepers 12 is of unitary form and is arranged completely within the shaft 10 in one corner thereof.

The said latching means includes a sectional tubular casing 13 consisting of sections 14, sections 15 which interpose the sections 14, and a lower section 16. The sections 14 are detachably connected between the sections 15 by any practical means, such as by the provision of bayonet slots 17 in the opposite ends of each section 14 and pins 18 on the adjacent ends of two of the sections 15 which enter the slots 17. It will therefore be understood that by imparting turning movement to each section 15, such section may be readily de-

tached. The casing 13 is supported in any suitable manner such as by the use of attachments 19 secured to the wall of the shaft 10. The lowermost section 15 of the casing being supported against downward movement by the lowermost attachment 19, while the remaining sections 15 are loosely held in position by the remaining attachments 19, so that they may be moved whenever desired for the purpose of detaching the sections 14. The sections 14 are disposed adjacent the doors 11, and the lowermost section 16 is disposed adjacent an opening in the wall portion of the shaft in the basement. Each of the sections 14 with the exception of the uppermost section 14 has arranged therein an element 20 consisting of a cross sectionally round tubular member 21, latch member 22 formed integral with the member 21 and a member 23 also formed integral with the member 21. A bolt 24 extends through the member 21 and through holes arranged diametrically opposite each other in the section 14. A nut 25 is applied to one end of the bolt 24 to hold the same against axial movement. The bolt 24 serves as an axis for the element 20. The section 14 has a slot 26 therein which enables the latch member 22 to be moved to the latching and unlatching positions. The latch member 22 is movable into and out of engagement with the keeper 12 on the related door 11. The element 20 is under the influence of a contractile spring 27 which has one end thereof connected as at 28 with a transverse partition 29 forming a part of the section 14, and the opposite end of said spring is connected by links 30 with the eye 31 on the latch member 22. The spring 27 has a normal tendency to move the element 20 to a position in which its latch member 22 will engage the related keeper 12. Movement of the element 20 is accomplished by the employment of a flexible element which may be in the form of a stout cord, chain or cable. In the present instance use is made of a cable 32 which has one end thereof connected as at 33 with the member 23, and the lower end thereof is connected as at 34 with a retaining element 35 arranged exteriorly of the lower section 16. It will be apparent that the cable 32 extends within the casing 13 and has guided movement over small grooved rollers 36 supported by the partitions 29 of the casing sections. The element 35 is pivotally mounted as at 37 so as to be swung downwardly to impart movement to the element 20 against the action of the spring 27 to disengage the latch member 22 from the related keeper 12. The element 35 will be held in the down position against being moved upwardly by the action of the spring 27 by reason of its angular disposition, when it is in the down position, and due to the weight of the element 35. The element 20 is released to the action of its spring 27 when the janitor or superintendent

imparts upward movement to the element 35. In this manner each door may be latched against being opened by a tenant. It is to be understood that each door 11 is hingedly mounted and opens inwardly of the apartment. It is also to be understood that suitable identification marks may be placed on the elements 35 to correspond to the different apartments. 70

The two uppermost doors 11 which are arranged opposite each other are controlled by a double latch. This double latch is disclosed most clearly in Figs. 3 and 4. The latch elements 20 of this double latch are mounted on the same bolt 24 for pivotal movement. 75 The latch members 22 extend relatively in opposite directions, one of the members being considerably longer than the other in order to reach across the shaft. The members 23 are connected with the same flexible element 32 by 80 link connections 38. It will therefore be understood that by manipulating the element 35 of this double latch, both latch members 22 will be moved simultaneously to the latching and unlatching positions. Consequently 85 it will be possible to latch and unlatch the two uppermost doors 11 simultaneously. 90

I claim:

1. In combination with a dumb-waiter shaft having doors at different levels, latch means for each of the doors, and actuating means located at the bottom of said shaft for each latch means and operatively connected therewith to actuate the same to latch and unlatch the related door. 95

2. In combination with a dumb-waiter shaft having doors at different levels, latch means for each of said doors and adapted to normally latch the door, and actuating means located at the bottom of said shaft for each latch means and operatively connected therewith to actuate the latter to unlatch the related door. 105

3. In combination with a dumb-waiter shaft having doors affording access to the interior of the shaft and each being mounted to swing outwardly, a keeper on the inside of each door, a support extending vertically within said shaft, a latch device positioned on said support for each keeper to cooperate therewith to latch the related door, and means positioned on the lower end of said support for each latch device to operate it to unlatch the door. 115

4. In combination with a dumb-waiter shaft having doors affording access to the interior of the shaft, a keeper on the inside of each door, a spring actuated latch device positioned within said shaft for each keeper and normally in engagement with said keeper to latch the door, and means located at the bottom of said shaft for each latch device and operatively connected therewith to operate the same to unlatch the door. 125

5. In combination with a dumb-waiter 130

shaft having doors arranged opposite each other affording access to the interior of the shaft, latch means positioned within said shaft and adapted to latch said doors, and 5 means located at the bottom of said shaft operatively connected with said latch means to operate it to latch and unlatch said doors.

6. In combination with a dumb-waiter shaft having doors affording access to the 10 interior of the shaft, a keeper on the inside of each door, a pivoted latch member positioned within said shaft for each keeper, yieldable means acting on each latch member which retains the latch member engaged with 15 the keeper to latch the door closed, and means located at the bottom of said shaft for each latch member and operatively connected therewith to retract the latch member from engagement with its keeper to unlatch the 20 door.

7. In combination with a dumb-waiter shaft having doors affording access to the interior of the shaft, a keeper on the inside of each door, a pivoted latch member positioned 25 within said shaft for each keeper, yieldable means acting on each latch member which retains the latch member engaged with the keeper to latch the door closed, and means located at the bottom of said shaft for each 30 latch member and operatively connected therewith to retract and to retain the latch member from engagement with its keeper to unlatch the door.

8. In combination with a dumb-waiter 35 shaft having doors affording access to the interior of the shaft, a keeper on the inside of each door, a tubular casing positioned within said shaft, said casing consisting of sections certain of which are detachable, the 40 detachable sections being positioned respectively adjacent said doors, a latch device on each of said detachable sections normally adapted to engage the keeper of the adjacent door, a manipulator for each latch device positioned on the lowermost section of said casing, and a flexible element connecting said manipulator with its related latch and having guided movement within said casing to 45 operate the latch device in response to the manipulation of the manipulator, for the 50 purpose of latching and unlatching the related door.

9. A latching device comprising a tubular casing, spring actuated latches positioned 55 within said casing at different points intermediate the opposite ends thereof, and means on one end of the casing for each of said latches operatively connected therewith, to move the latch to a latching position, there 60 being a slot in the casing through which the latch may project, the latch being sufficiently long to project through said slot.

10. A latching device comprising a tubular casing consisting of sections, said sections 65 having provision whereby the sections may

be detached from each other, spring actuated latches operatively positioned within certain of said sections, and means on one of the end sections for each of said latches operatively connected therewith, to move the latch to a latching position, there being a slot in the casing through which the latch may project, the latch being sufficiently long to project through said slot.
